VARIABLE HIGH-FREQUENCY COIL AND/OR
TUNING ASSEMBLY

Martin V. Kiebert, Jr., Birmingham, Mich., and
Alfred S. Backus, Passaic, N. J., assignors to
Mycalex Corporation of America, Clifton, N. J.,
a corporation of New York

Application July 6, 1951, Serial No. 235,454

5 Claims. (Cl. 250—40)

1

This invention relates to an improved variable high-frequency coil and/or tuning assembly.

An object of the invention is to provide an improved high-frequency coil in which the inductance can be varied and in which the various turns of the coils are insulated from each other and from the inductance-varying means by a material having high dielectric properties.

Another object of the invention is to provide an improved high-frequency tank circuit which is space-saving and compact, stable, and insensitive to vibration though variable.

Another object of the invention is to provide an improved high-frequency tank circuit which tends to maintain optimum inductance-capacitance ratios over a relatively wide tuning range.

These objects and others ancillary thereto are attained by fixing an inductance coil upon a tube of molded insulating material which is adapted to rotate with respect to the surrounding tube, the internal core carrying an electrical conductor which is constructed so as to vary the inductance of the coil upon rotation of the core with respect to the coil or tube.

Suitable means for mounting or fixing the device on a chassis or control panel are also provided.

The insulating material of which the coil-holding tube and internal core are constructed is preferably a glass-bonded mica product such as that sold under the trade name of "Mycalex." Other insulating materials, preferably with high dielectric strengths and low power factors, may be employed. Titanates of barium, strontium, etc. may be added to the insulating material to increase its dielectric constant.

Ordinarily, the distributed capacitance of the coil itself can be utilized to furnish the capacitance for a high-frequency tank circuit. The coils can be at least partially embedded in the tube or sleeve which is made of an insulating material, such as "Mycalex," which has a high dielectric constant so as to increase the distributed capacitance. In addition, condenser elements may be provided on the sleeve, which elements are so situated and constructed that rotation of the core changes the capacitance in such a way that maximum capacitance is obtained at the same time as maximum inductance and vice versa, whereby a greater range of resonance is obtained as well as a more desirable ratio of inductance to capacitance over the tuning range.

The novel features characteristic of this invention are set forth with particularity in the appended claims. The invention itself, however, both as to its organization and its method of op-

2

eration, together with additional objects and advantages thereof, will best be understood from the following description of specific embodiments when read in connection with the accompanying drawings, in which: Figure 1 is a side view (greatly enlarged) of one form of the device of the invention,

Figure 2 is a cross-sectional view of the device of Figure 1,

10 Figure 3 is a top view of a modified form of the device,

Figure 4 is a diagram illustrating the type of tank circuit obtained by the device of Figure 3.

The device comprises the tubular or sleeve member 10 upon or within which the coil 11 is secured, the internal rotor or core 20 and the attaching means 30.

20 The attaching means 30 can take any convenient form. As shown it is made of metal and comprises a projecting end 31 to which the tube 11 is attached, an annular flange 32 which supports and is integrally sealed to the tube 10 at one side and which also furnishes a bracketing surface for the attaching nut 33 at the opposite side. The end opposite the end 31 is threaded to receive the nut 33. An opening 35 extends through the member 30 to furnish a bearing surface for the shaft 21 of the rotatable core 20. A washer 36 may be included in the assembly.

25 The coil 11 is integrally molded into the sleeve member 10 and the axis of each of the mean individual turns 12, 13 and 14 of the coil 11 is at an acute angle (45°, for example) with respect to the axis of the sleeve 10 or rotor 20. As shown, about half of the diameter of wire on each of the turns 12, 13 and 14 is embedded in and firmly united to the tubular sleeve member 10. The opening 15 in the tube 10 is cylindrical and smooth and when glass-bonded mica is employed as the tube material the inside dimensions can be molded within close tolerances.

30 The rotor or core member 20 comprises the metal shaft 21 having the flange 22 and 23 at the end thereof adapted to securely clamp the molded insulating material of the body 25 of the rotor. Also molded into the rotor is the ring 24, the exposed surface of which is flush with the surface of the body 25. The body 25 is cylindrical and fits snugly within the cylindrical bore 50 15 of the tube 10. The flanged end 22, 23 of the shaft 21 is spaced from the nearest coil turn 12 so that the said metallic shaft 21 does not influence the inductance of the coil 11. In the position shown in Figure 2 the inductance of the device is at a minimum since the short-circuited

conducting ring 24 shorts out a certain portion of coil 11. Rotation of the rotor 20 by 180° will give a maximum of inductance.

In the modified form of the device shown in Figure 3, the rotor 20, and attaching member 30 have the same construction as in Figures 1 and 2, and like members refer to like parts in the various figures. The tubular stator element 10' of Figure 3 is constructed somewhat differently. Connected adjacent to the beginning of the first turn 12' is the conductor 40, and a flat capacitive element 41. Connected to the end of the last turn 14' is a conductor element 42 and flat capacitive element 43. The effect of the two capacitive elements 41 and 43 is to add capacitance to the distributed capacitance of the device. The capacitance is added in such a way as to considerably increase the tuning range of the device, i. e., as the inductance is increased by rotation of the core member 20, the capacitance is also increased since the ring 24 approaches closer to the elements 41 and 43 and vice versa as the inductance is decreased the capacitance is decreased. The effect is to more than double the tuning range.

As an example of how the device works, if the three-turn coil as shown is approximately 1 centimeter in diameter and at an angle of approximately 45°, and if glass-bonded mica is employed as the material of tube 10 and rotor 20, a frequency range of 215 to 228 megacycles is obtained without the aid of the added condenser elements 41 and 43. With the addition of the condenser elements 41 and 43, as shown, the frequency range is increased to from 205 to 245 megacycles.

It is readily apparent that the economies due to this invention are greater than those due to previously made coils in that the coils made according to this invention permit greater space saving in tight-fitting and compact assemblies and are protected by their accurate construction from various outside mechanical influences. Since the coil 11 is firmly united to the tube 10, it is permanently positioned and electrically accurate. For example, the fixed coil 11 is not influenced by vibrations or accidental blows. Since the rotor 20 fits snugly within the tube 10, it likewise is not influenced by vibration, etc.

We claim:

1. A combination tuning device consisting of an inductance comprising two terminals with at least one turn of a linear conducting material therebetween; a tubular sleeve of insulating material having a cylindrical opening therein, the turns of conducting material being embedded in the sleeve of insulating material with the axis of the mean coil turn being at an acute angle with respect to the axis of said tubular sleeve; a cylindrical rotor comprising a body member of insulating material having a ring of conducting material embedded therein with the axis of said ring at an acute

angle with respect to the axis of the rotor, with means distant from the said ring adapted to rotate said rotor.

2. The device of claim 1, in which the insulating material of said sleeve and said rotor consists of glass-bonded mica.

3. A combination tuning device consisting of an inductance comprising two terminals with at least one turn of a linear conducting material therebetween; a tubular sleeve of insulating material having a cylindrical opening therein, the turns of conducting material being embedded in the sleeve of insulating material with the axis of the mean coil turn being at an acute angle with respect to the axis of said tubular sleeve; a cylindrical rotor fitted within said cylindrical opening of said sleeve, said rotor comprising a body member of insulating material having a ring of conducting material embedded therein with the axis of said ring at an acute angle with respect to the axis of the rotor; a pair of capacitive elements fixed at opposite sides of said sleeve member and each connected to a different one of said terminals.

4. The device of claim 3 in which the insulating material of said sleeve and said rotor consists of glass-bonded mica.

5. A combination tuning device consisting of an inductance comprising two terminals with at least one turn of a linear conducting material therebetween; a tubular sleeve of insulating material having a cylindrical opening therein, the turns of conducting material being embedded in the sleeve of insulating material with the axis of the mean coil turn being at an acute angle with respect to the axis of said tubular sleeve; a cylindrical rotor fitted within said cylindrical opening of said sleeve, said rotor comprising a body member of insulating material having a ring of conducting material embedded therein with the axis of said ring at an acute angle with respect to the axis of the rotor; a pair of capacitive elements fixed at opposite sides of said sleeve member and each connected to a different one of said terminals and with means insulated from and distant from said inductance member adapted to secure the device to a control panel.
